UNITED STATES PATENT OFFICE

149,900

DESIGN FOR A LAWN SWING OR SIMILAR ARTICLE

Charles Louis Mock, Newark, Ohio

Application May 27, 1946, Serial No. 130,116

Term of patent 3½ years

(Cl. D15—11)

To all whom it may concern:

Be it known that I, Charles Louis Mock, a citizen of the United States, residing at Newark, in the county of Licking and State of Ohio, have invented a new, original, and ornamental Design for a Lawn Swing or Similar Article, of which the following is a specification, reference being had to the accompanying drawing, forming a part thereof.

Fig. 1 is a perspective view of a lawn swing or similar article showing my new design;

Fig. 2 is a top plan view of the swing;

Fig. 3 is a side elevational view thereof.

I claim:

The ornamental design for a lawn swing or similar article, substantially as shown.

CHARLES LOUIS MOCK.
